UNITED STATES PATENT OFFICE.

ROBERT LUCAS, OF MACON, GEORGIA.

MECHANISM FOR RAISING THE WEIGHTS OF DRAWING-ROLLERS.

SPECIFICATION forming part of Letters Patent No. 460,302, dated September 29, 1891.

Application filed February 13, 1891. Serial No. 381,330. (No model.)

To all whom it may concern:

Be it known that I, ROBERT LUCAS, of Ma-
con, in the county of Bibb and State of
Georgia, have invented certain new and use-
ful Improvements in Mechanism for Raising
the Weights of Drawing-Rollers; and I do
hereby declare the following to be a full, clear,
and exact description of the invention, such as
will enable others skilled in the art to which
it pertains to make and use it, reference be-
ing had to the accompanying drawings, which
form part of this specification.

My invention relates to an improvement in
mechanism for raising the weights in cotton,
woolen, or worsted machinery; and it consists
in the combination and construction of parts
which will be fully described hereinafter, and
particularly referred to in the claim.

The object of my invention is to provide a
means whereby all of the weights can be lifted
from the top rolls at the same time, thus sav-
ing time, labor, and covering for the rolls, and
trouble in removing and replacing the top rolls.

Figure 1 is a vertical section taken through
the top rolls of a cotton, woolen, or worsted
spinning or twisting machine, to which my
invention is applied. Fig. 2 is a detail view
of the same.

A represents the top roll; B, the bottom roll;
C, the usual top hooks which catch over the
top rolls; D, the bottom hooks, and F the
weights, which are hung upon the hooks D in
the usual manner.

Extending transversely across the frame
below the top rolls and below the lower ends of
the top hooks C are the bearings G, which form
supports or bearings for the rod H, which ex-
tends parallel with the rolls. For each set of
weights there is a lever I, which is supported
at its rear end upon the rod H, and each lever
extends across under the rolls and engages
with the bottom hooks in any suitable man-
ner, so that all of that set of hooks and weights
can be raised, so that the top roll will be freed
from them all at once.

The front end of each of the levers I is pref-
erably shaped as shown, and rests upon the
rod J, which is secured by brackets L to the
angular shaft O, which is supported upon the

opposite end of the bearing G from the rod 50
H. This shaft O has secured to one end a
worm or other suitable wheel P, by means
of which the shaft is made to revolve for the
purpose of causing the rod J to sweep through
a portion of a circle, and thus act as a cam to 55
raise one end of all the levers I at the same time.
The wheel P is preferably operated by a worm
Q, which is journaled in a suitable frame R
and provided with a handle S. By turning
the handle the shaft is made to revolve, and 60
as the rod J sweeps around the front ends of
the levers I are raised and lowered at will for
the purpose of applying the weights to or re-
moving them from the top rolls all at once.

By means of the mechanism here shown 65
and described the weights can be raised to
any desired height, or can be raised just high
enough to take the top hooks off without the
bottom hooks falling down, thus saving the
operator the time and trouble of raising the 70
weights by hand when putting on the top rolls.
This construction also effects a great
saving in the covering of the rolls, for the
weights can all be raised when not in use, and
saves time and trouble in taking the rollers 75
out and returning them to position, as no
skilled labor is required.

Having thus described my invention, I
claim—

In a device of the character described, a 80
supporting-frame, levers pivoted therein at
one end, a shaft journaled in the opposite end
of the said frame, carrying an eccentric or
crank which the free ends of the levers engage,
a cog-wheel secured to the said shaft, a U- 85
shaped frame secured to the supporting-frame
and carrying a worm-gear which engages the
said wheel, the rolls, weights connected with
the rolls, and stops connected with the weights
which engage the upper sides of the levers, 90
the parts combined substantially as shown
and described.

In testimony whereof I affix my signature in
presence of two witnesses.

ROBERT LUCAS.
